ARTHUR W. SMITH, OF NEW YORK, N. Y., ASSIGNOR TO REMINGTON TYPEWRITER COMPANY, OF ILION, NEW YORK, A CORPORATION OF NEW YORK.

TYPE-WRITING MACHINE.

1,116,144.

Specification of Letters Patent.

Patented Nov. 3, 1914.

Application filed August 9, 1913. Serial No. 783,924.

To all whom it may concern:

Be it known that I, ARTHUR W. SMITH, citizen of the United States, and resident of the borough of Manhattan, city of New York, in the county of New York, and State of New York, have invented certain new and useful Improvements in Type-Writing Machines, of which the following is a specification.

10 My invention relates to typewriting machines and, more particularly, to the escapement mechanism which controls the feed of the carriage.

15 My invention has for its principal object to provide improved escapement mechanism of simple and inexpensive construction, but thoroughly good and efficient.

20 My invention also includes improved means whereby the carriage can be withdrawn toward the right without operating the carriage release device.

25 To the above and other ends, my invention consists in certain features of construction and combinations and arrangements of parts, all of which will be fully set forth herein and particularly pointed out in the claims.

30 In the accompanying drawings, Figure 1 is a partial front-to-rear, vertical sectional view of a typewriting machine having my invention embodied therein. Fig. 2 is an enlarged view similar to part of Fig. 1 but with the section taken on a different plane. Fig. 3 is an enlarged rear elevation. Fig. 4

35 is a bottom view of the escapement bracket.

My invention is applicable or readily adaptable to various forms of typewriting machines.

40 The machine of which parts are illustrated in the drawing, has a main frame on which is mounted a stationary carriage rail 1 having in its front and rear edges grooves forming race-ways for antifriction balls 2, which balls coöperate with the front and rear rails 3 of a carriage, which carriage also includes end pieces 4 and various connecting devices, such for example, as a rod or shaft 5. In said end pieces 4 there is suitably journaled a platen 6 with which co-operate certain paper feed devices, not illustrated. The machine is provided with any suitable printing mechanism. I have here shown a printing key lever 7 pivoted on a transverse wire 8 and having at its rear end

55 an upright push link 10. These are merely

typical of any suitable printing mechanism, the parts shown constituting a portion of a type action which is fully described and claimed in my pending application Serial No. 763,532, filed April 25, 1913. The key 60 levers 7 are levers of the first order and a universal bar 11 lies across the rear arms of said levers, said universal bar being part of a yoke-frame, which yoke-frame also comprises arms 12 pivoted at 13 in the stationary 65 framework. The carriage can be provided or connected with any suitable escapement rack.

14 designates a straight escapement rack bar having teeth 15 on its under side and suitably secured to a strip of angled metal 16 which at its ends is fastened to arms 17 pivoted at 18 in the end pieces 4 of the carriage. A release key, not shown, is provided whereby the rack 14 can be lifted, the arms 70 17 turning about their pivots 18. Said rack is held down normally by one or more springs 20.

The escapement mechanism is mostly mounted on a bracket 21, which bracket is 80 secured to the under side of the stationary rail 1 by screws 22. Said bracket comprises two arms 23 inclined downward and toward the rear of the machine as shown in Fig. 1, and connected together by a cross bar or 85 part 24. Said bracket also comprises two lugs 25, Fig. 2, whose upper surfaces rest against the rail 1 and through which the screws 22 pass.

The dog rocker 26 is made of a single 90 piece of sheet metal stamped out to suitable outline and bent up in the manner illustrated. Said dog rocker includes two ears 27 bent toward the rear from the main plane of the rocker and formed with conical holes 95 by which said dog rocker is pivoted on coned pivot pins or screws 28 threaded through the extremities of the arms 23 whereby said dog rocker is pivoted to the stationary framework of the machine.

100 The means for operating the dog rocker comprises an arm 30 bent off at 31 into a plane at right angles to the main plane of the rocker and again bent at 32 at a suitable inclination downward and toward the rear of the machine. It will be perceived that by this double bend any suitable inclination can be given to this arm 30. Said arm at its lower end stands just in rear of the upper end of an arm 33 projecting upward from 110

the universal bar 11, on which it is rigidly mounted approximately at the middle of said universal bar. The construction is such that when one of the keys 7 is operated and 5 the universal bar is moved upward, the upper end of said arm 33 pushes the lower end of the arm 30 toward the rear and upward and rocks the dog rocker about its pivots 28. A restoring spring 34 is connected 10 at one end to the arm 30 which is perforated at 35 for the purpose, and the other end of said spring is connected to the rear end of a plate 36 which is secured by means of screws 37 to the under side of the cross bar 15 24 of the bracket 21. Said screws 37 pass through elongated slots 38 in said plate, so that said plate 36 is adjustable in a front and back direction. Said plate at the rear part thereof is formed with an off-set in 20 which is a slot 40, which slot embraces one edge of the dog rocker 26 and is of a suitable width to allow said dog rocker a proper amount of swinging motion about its pivot. One wall of this slot acts as a stop to limit 25 the rearward motion of the dog rocker, and the other wall of the slot acts as a stop to limit the forward motion of the dog rocker, the two stops being adjusted together by moving the plate toward the front or toward 30 the rear, after which said plate is secured by tightening the screws 37.

The feed dogs are two in number, one dog 41 being pivoted on a pivot screw 42 screwed into the rear face of the dog rocker 35 26. This dog has two branches, a horizontal branch to which the reference numeral 41 is directly applied in Fig. 3 and which branch lies substantially parallel with the line of motion of the rack 14, and another branch 40 43 extending away from said rack and having a second dog 44 pivoted thereto on a pivot 45 situated at a distance from the rack so that said dog 44 extends from the pivot 45 toward the rack and is capable of 45 vibrating about said pivot in the direction of travel of said rack. The dog 41 has a rack-engaging tooth 46 consisting of an ear of the sheet metal of which the dog is composed, said ear being bent toward the front 50 of the machine at right angles to the plane of the dog. The dog 44 has a similar rack-engaging tooth 47 but this latter is bent out of the plane of the dog toward the rear of the machine. The dog 44 has an arm 48 to 55 which is connected one end of a spring 50, the other end of which is connected to a pin 51 projecting from the rear face of the dog rocker 26. The direction of pull of this spring is such as to tend to rock the dog 60 44 about its pivot and to move the tooth 47 of said dog in a direction contrary to the direction of feed movement of the rack 14. The motion of said dog 44 about its pivot 45, is limited in both directions by a pin 52 65 projecting from the dog 41 into a notch

included between the main body of the dog 44 and an arm or branch 53 of said dog. The spring 50 also acts through the dog 44 on the dog 41, tending to rock said dog 41 upward about its pivot 42; and the motion of said dog 41 in this direction is limited by a toe 54 of the arm 43 of said dog, which toe normally presses against the under side of one of the ears 27 of the dog rocker. 70

In order to guide the two dogs 41 and 44, the sheet metal dog rocker has an arm 55 formed thereon and this arm is bent back upon the main body of the rocker so as to lie behind the dog 44 and parallel with the plane of the dog rocker, thus leaving between the body of said dog rocker and said arm 55 a slot of suitable width to guide the two dogs. 80

The carriage can be fed toward the left by any suitable means. I have here shown 85 a cord 56 one end of which runs over a spring drum, not shown, and the other end of which is connected to a fixture 57 which is secured to one of the carriage rails 3 by a screw 58. 90

The two dogs are shown in the drawing so arranged as to have the action of a reverse escapement, that is to say, the carriage is released on the down stroke of the key. This is brought about by reason of the fact that it is the dog 41 that normally engages the rack teeth 15 and the dog 44 normally stands in the position shown in the drawings where it is free from the rack and where its tooth 47 is ready to move into 100 engagement with the next oncoming tooth 15 of the rack. When a key is depressed and the universal bar is operated, this tooth 47 moves into engagement and the tooth 46 moves out of engagement, leaving the rack 105 free to take one step, limited by the pin 52. On the up stroke of the key the tooth 46 of the dog 41 moves into engagement with the same tooth that was caught by the dog 44 and said dog 44 moves out of engagement 110 and is restored to its normal position by the spring 50. When the carriage is pushed toward the right without raising the rack 14 out of engagement with the dogs, then the rack teeth cam down the feed dogs, which 115 dogs move downward together, turning about the pivot 42 as a center, this motion downward being resisted by the spring 50. In order to produce this downward motion of the dogs, each of the teeth 15, 46 and 47 120 is made inclined on its reverse face as shown. It will be perceived that the dogs will be cammed down whichever one of the dogs is in engagement with the rack at the time. Ordinarily it would be the dog 41 that 125 would be in engagement during this operation; but if the carriage was moved toward the right while a printing key or space key was held down and when, therefore, the tooth 47 was in engagement with the rack, 130

this camming down operation would take place just the same. It is for this reason that the dog 44 is mounted on the dog 41.

It will be perceived that the spring 50 performs the double function of rocking the dog 44 about its pivot and also of holding both dogs in rack-engaging position, restoring said dogs to such position by turning them about the pivot 42 as a center.

10 It will be perceived that this entire escapement, including the dog rocker, the two dogs, and the adjustable stop for limiting the motion of the dog rocker, consists chiefly of four pieces punched out of sheet metal; 15 and yet the mechanism is thoroughly substantial and efficient.

It will be perceived in Fig. 1, that normally the arm 33 is not in contact with the arm 30 and this is the preferable construction because it is desirable that the dog rocker move only a short distance and this only when the printing key is near the bottom of its stroke. The precise relation between the arms 30 and 33 can be regulated 25 by an adjustment of the arm 30 made by bending the metal along the line 32.

It is not essential that the teeth 46 and 47 be made by bending in the manner described, but teeth suitable for the purpose 30 can be produced without the bending operation by using heavier stock. In one form of the escapement that I have made and found satisfactory, the dog 41 is made of heavier stock than indicated herein and the tooth 35 thereof that engages the rack is not bent, the dog 44 being made, as herein shown, with the bent-off tooth.

I prefer to have the loose dog 44 beveled and this is brought about as indicated in 40 Fig. 3 by bending off the tooth 47 through somewhat less than a right angle from the plane of the main body of the dog. When the tooth 47 is in engagement with the rack 15 there is, besides said beveling, nothing 45 but the tension of the restoring spring 34 to pull said tooth out of the rack; and it is, of course, desirable that this spring be not too heavy. By beveling the dog as shown, the pressure of the rack against it is at such an 50 angle as that said pressure itself tends to overcome its own friction and to remove the loose dog out of the rack and bring the parts back to normal position.

It will be noted from what has been said 55 that the escapement shown is a reverse escapement and that the restoration of the dog rocker to normal position is done independently of the universal bar. That is to say, that whereas the arm 33 can move the 60 arm 30 toward the rear of the machine, it cannot exert any pressure to restore it to normal position; and the loose dog or normally disengaged dog is itself beveled in order to assist in this restoration, if necessary. The beveling of this dog also has the

usual result of beveling any other dog, namely, that the carriage is feeding during the time when the dog is moving out of engagement with the rack and without waiting for the dog to become entirely disengaged from the rack. 70

Various changes can be made in the details of construction and arrangement without departing from my invention.

What I claim as new and desire to secure by Letters Patent, is:—

1. The combination with an escapement rack, of a dog rocker consisting of a piece of sheet metal pivoted to the frame of the machine and having an arm thereof bent 80 back to constitute a guide, and a feed dog pivoted to said rocker and guided by said bent back arm.

2. The combination with an escapement rack, of a dog rocker consisting of a piece 85 of sheet metal pivoted to the framework of the machine and having an arm bent back to constitute a guide, a feed dog pivoted to said rocker, and a second feed dog pivoted to the first mentioned dog, both of 90 said feed dogs being guided by said bent back arm.

3. The combination with an escapement rack, of a dog rocker, a feed dog mounted 95 on said rocker and movable with relation to said rocker into and out of engagement with the rack, a second feed dog movably mounted on the first feed dog, and a spring acting on said second feed dog and through it on the first dog. 100

4. The combination with an escapement rack, of a dog rocker, the dog pivoted to said rocker so as to swing about its pivot into and out of engagement with the rack, and said dog having an arm or branch extending away from said rack, and a second dog pivoted to said arm or branch so as to swing in a direction parallel with the direction of rack movement. 105

5. The combination with an escapement 110 rack, of a dog rocker, a dog pivoted to said rocker so as to swing about its pivot into and out of engagement with the rack, and said dog having an arm or branch extending away from said rack, a second dog 115 pivoted to said arm or branch so as to swing in a direction parallel with the direction of rack movement, and a spring connected with said second dog and acting to swing both dogs about their respective 120 pivots.

6. The combination with an escapement 125 rack, of a feed dog having two branches one lying parallel with said rack and the other extending away from said rack, a dog rocker to which the former of said arms is pivoted, and a second dog pivoted to the latter of said branches.

7. The combination with an escapement rack, of a dog rocker, a sheet metal dog 130

5 pivoted to said rocker and having an ear thereof bent off to constitute a tooth for engagement with said rack, said dog also having a toe for coöperation with a part of said dog rocker and acting as a stop to limit the motion of said dog about its pivot, and a second dog pivoted to the first mentioned dog.

8. The combination with an escapement rack, of a sheet metal dog rocker having ears thereof pivoted in the framework of the machine and having an arm thereof bent into a plane at right angles to the plane of the dog rocker, actuating means coöperating 15 with said arm, and means mounted on said dog rocker for coöperation with said rack.

9. The combination with an escapement rack, of a dog rocker, a dog arm pivoted

to said dog rocker, another dog arm pivoted to the first said dog arm, a stop on the first 20 dog arm to engage a fixed stop, a spring acting on both said dog arms and normally holding said stops in contact, said spring permitting the second dog arm to be moved with the rack and then acting to return 25 said dog arm to normal position when released from the rack without disturbing the tension of said spring on the first dog arm.

Signed in the borough of Manhattan, city of New York, in the county of New York, and State of New York, this 8th day of August, A. D. 1913.
